US00D433729S

United States Patent [19]**Poirier et al.****Patent Number: Des. 433,729****Date of Patent: ** Nov. 14, 2000**[54] **FILTRATION BOTTLE WITH CAP**

[75] Inventors: **Malcolm Daniel Poirier**, Marietta, Ga.; **Paul Metaxatos**, Collinsville; **David Mathieu**, Middleton, both of Conn.; **Jeffrey Eldon Fish**, Dacula; **Kevin Peter McGrath**, Alpharetta, both of Ga.

[73] Assignee: **Kimberly-Clark Worldwide, Inc.**, Neenah, Wis.

[**] Term: **14 Years**

[21] Appl. No.: **29/110,112**

[22] Filed: **Aug. 31, 1999**

[51] LOC (7) Cl. **23-01**

[52] U.S. Cl. **D23/209; D7/507**

[58] Field of Search D23/207, 209; D7/507, 510, 511; 215/355; 210/282, 266

[57] **CLAIM**

We claim the ornamental design for a filtration bottle with cap, as shown and described.

DESCRIPTION

FIG. 1 is a perspective view a filtration bottle with cap showing our new design;

FIG. 2 shows a side elevational view of an alternate embodiment of FIG. 1, with the only difference being that the cap is transparent; and,

FIG. 3 is a top view thereof.
